ALARM SYSTEM

Ralph L. Hughes, Los Angeles, Calif.

Application April 3, 1945, Serial No. 586,349

2 Claims. (Cl. 177—314)

1

This invention relates to automatic alarm systems informing police stations, fire departments or other private or public agencies keeping watch over the premises of a shop or other establishment that alarming conditions have developed and it has particular reference to systems of this type in which messages are sent by wireless transmission.

It is the general object of the invention to improve alarm systems of the above mentioned type in such a way that they are able to work satisfactorily and reliably in conjunction with the existing facilities of police stations, fire departments and other agencies without disturbing other installations and without requiring the presence or installation of a special network while on the other hand, a reasonable security exists that the call will be received.

According to the invention the message is a spoken message which is delivered repeatedly during a given period and which is sent out by radio by means of a transmitter which is able to cover a certain limited area which includes several stations, but not too many stations, equipped for the reception and supervision.

The transmitter is set into operation by local alarm circuits and the operation of said alarm circuits also selects one of a series of automatic endless records which are operated when the alarm signal is given and which furnish the modulation for the transmitter so that the received waves will indicate by means of a spoken message the nature of the disturbance and its location.

The invention also includes means for stopping the record and the operation of the transmitter after a sufficient number of alarm signals have been transmitted and includes means for automatically resetting the entire alarm system for a later operation.

The invention further comprises means for sending a spoken message which are controlled by the operation of the transmitter itself.

The invention further comprises means for timing the operation of the transmitter and of the record producing the talking in such a way that they are operated simultaneously.

Further features of the invention and further objects to be attained will be described in the following specification.

It is to be understood that the invention resides mainly in the alarm system as described and shown in the specification and drawings, and as claimed; the description of one modification of this system is not intended to be limitative but

5 to show by way of example how this system can be carried into effect. Many changes especially with regard to specific details mentioned may, therefore, be made without departing from the essence of the invention.

In the accompanying drawings:

Figure 1 is a diagram of the connection of an installation producing two different types of alarm.

Figures 2 and 3 are diagrams showing different methods for producing the talking currents from an endless record, which may be employed in the alarm system according to the invention.

Figure 4 is a diagrammatic view of one type of automatic switch that may be employed in the local alarm circuits.

Figures 4a to 4c illustrate different positions of the switch.

Figure 5 is a top view on the endless steel wire arrangement on an enlarged scale.

Figure 6 is a diagrammatic view of a further modification.

According to the modification shown in the diagram (Figure 1) the installation comprises two different types of alarm systems each provided with its own endless record for a spoken message. One of these messages may be, for example, a message to the police department to be delivered when the burglary alarm is operated and the second message may be one for the fire department in the event that one of the switches of the fire alarm circuit is operated. It is, however, to be understood that this represents merely an example for a typical case and that the number of messages among which the correct message has to be selected may be larger.

The alarm is given as usual by means of a number of switches 3, 13 or 33 connected in parallel. In the example shown (Figure 1) the (automatic) burglar alarm switches 13 are controlled by a key-operated switch 32 which, when operated, permits said switches 13 to be energized from outside of the premises, while the push-button type of emergency police alarm switches 3 and also the thermally operated fire alarm control switches 33 may be energized at all times whether the key switch is operated or not. The switches 13 in this diagram (Figure 1) are automatic re-opening switches which, upon being operated by a burglar opening a door or window or some other means, close their contacts only momentarily and then remain in an open position until again operated by the above described means.

The closing of one of the switches 3, 13 or 33 closes the alarm circuit, as well known, to which

the group of switches belongs. Assuming, for instance, that the switches 13 belong to a group forming part of the burglary alarm, then each of them will close the alarm circuit 10 (Figure 1) which includes the alarm relay 12 operating a number of relay arms closing local circuits. Similarly the thermal switches 33 when operated will close the circuit 100 of relay 101, operating a number of local circuits. These local circuits control a transmitter 22 and a motor 42 which drives the endless speech record carrier apparatus 40 producing a talking current. The local circuits also include the coils 50, 51 of the magnetic heads of a magnetic recorder in which the currents modulating the carrier wave of the radio transmitter are induced. They further include switch arms 130, 130a and the contacts 49, 49a which provide means for stopping the operation of the entire alarm system, the holding circuits for the relays 12, 101 themselves, the filament circuit tubes 29, arranged in the output circuit of the transmitter and the grid circuit for the grid of tube 29 which is connected with a point of the transmitter supplying the desired grid bias for the operation of said tube.

The transmitter 22 may be of any well known type. In this special example the transmitter is supposed to operate only with one frequency. However, the transmitter is preferably adjustable to a number of different frequencies, if necessary. The transmitter should be adjustable to the broadcast wave length and moreover to the wave lengths used by police and fire departments' communication systems, the latter being as a rule short-wave communications systems.

The transmitter may be either battery operated or operated by connection with a source of electric power by means of the wall plug 30 and of the contacts 23 and it is set into operation by means of the contacts 24 which control the supply current through the relay arm 17 of the alarm relay 12. A series of contact terminals 26, 27 connects the transmitter with the circuits providing the talking currents.

A relay 28 is inserted in the place circuit of the electronic tube 29. The voltage for this circuit is supplied by the high-voltage plate current supply of the transmitter itself and is connected to the relay 28 and the electronic tube 29 through the contact terminals 36 of the transmitter 22. The relay contact arm 31 of the relay 28 controls the current supply to the motor 42.

The filament circuit of the electronic tube 29 is controlled by the contact arms 18, 118 of the relays 12, and 101 respectively.

The apparatus 40 furnishing the talking currents consists of a magnetic record carrier using endless magnetized wires 41, 41a, running over a series of grooved disks 45, the number of which is so chosen that they can accommodate the required wire length (Figure 5). Since the magnetized recording wires are endless the recorded message may be repeated over and over again for the desired number of times without any adjustments or any re-setting.

The disks 45 are driven by a pulley 43 which is itself driven by means of appropriately chosen gear wheels 44 by a motor 42. The coils 50, 51 of the magnetic head of the recorder are arranged near the wires in which the talking currents are induced.

The pulley drives a shaft 39 carrying a worm 46 which meshes with a worm wheel 47 carrying either a cam disk or a pin 48 acting on a pivoted switch actuating arm 124. The arm 124 is under

the tension of a spring 125 which draws it against a rest 126.

Against the switch actuating arm 124 which may be provided with a plate a push rod 127 bears which is connected with the two pivoted switch arms 130, 130a drawn towards the switch actuating arm by a spring 128. The switch arms 130, 130a cooperate with contacts 49 and 49a respectively. The switch arms 130 and 130a and contacts 49, 49a are so arranged that a slight movement of the arms will not separate them from the contacts, such separation being only the result of a movement of the arms over an appreciable distance.

When the pin 48 during revolution of the worm wheel is pushed against the switch actuating arm 124, the latter is therefore lifted from its rest 126 while the push rod 127 still rests on the push plate of the spring actuating arm for some time and the spring 128 keeps these two members in contact. This movement is however so slight that the contact arms 130 and 130a remain in contact with the contacts 49, 49a. When the pin 48 is moved further towards the switch actuating arm 124 the switch actuating arm moves away from its rest 126 and when the pin reaches the end of the switch actuating arm 124 the latter snaps back and first meets the push rod 127 exercising a kind of hammer like action. Thereby the two contact arms 130, 130a are driven out of engagement with contacts 49, 49a. This opens the circuits of said contacts momentarily. They do not remain open, however, but are soon closed again by the action of spring 128. The worm gear arrangement is so adjusted that the worm wheel 47 will complete one revolution by the time the recorded message on the endless wire has been broadcast for the desired number of times.

It will be noted that there are as many wire systems 41, 41a as there are different kinds of spoken messages to be sent over the transmitter. The connection of each system with the transmitter is controlled by the alarm circuits 10, 100, each circuit connecting one of the coils 50, 51 with the transmitter and thus selecting the special message to be transmitted.

It is to be understood, however, that the magnetic speech recording system (Poulsen system) is only an example and that other systems may be employed. Figures 2 and 3 show other methods which may be used. Figure 2 shows an endless strip or band 41c covered with a suitable surface layer or consisting of a suitable plastic material into which a record has been impressed by means of the usual cutter. The arrangement is otherwise the same which has been described with reference to Figure 1. The talking currents in this case are produced in the electric pick up 60 and may be amplified in the well known type of amplifier. Wires 62 and 63 are in this case connected over the relay contact with one of the contact pairs 26 or 27 of the transmitter. The rollers 45 over which the band is running are driven by means of a pulley 43 and by means of gear wheels 44 by a motor 42.

A similar arrangement is shown in Figure 3 in which an endless band 41b is covered by an emulsion rendered more or less opaque, by exposure to light in a photographic process or by printing or by using a triangular cutter penetrating more or less deeply into an opaque layer of varying thickness. The arrangement comprises a lamp 94 sending light rays to a photoelectric cell 96 arranged in a local circuit which may contain an amplifier. The leads 62, 63 lead

ing from the amplifier are then connected in the same way in which the coil 50 or 51 is connected with the contact terminals 26 or 27 of the transmitter 22.

An example of the type of switch that may be used as an automatic burglar alarm switch 13 is shown diagrammatically in Figures 4, 4A, 4B and 4C. As shown in these figures when the window (or door, etc.) 1 is opened by an unauthorized person entering the premises the pin 2 on the door or window pushes the arm 3a and shaft 4 in the direction shown by the arrow until the arm slips off the pin 2. At this moment the spring 5 pulls shaft 4 back against the stop 6. When the shaft strikes the stop 6 the momentum causes the weighted contact 8 on the flexible shaft 7 to continue moving so that it makes a momentary contact with the contact 9 which is also on a flexible shaft 10a. This momentary contact of the switch contacts 8 and 9 is sufficient to energize the alarm relay 12 in Figure 1 and starts the operation of the entire alarm system. After the momentary contact has been made the two switch contacts 8 and 9 (Figure 4) again resume their normal open position. The hinged arm 3a is counterbalanced so that it will always resume its normal position shown in Figure 4. This is provided because when the window 1 is closed the pin 2 causes the arm 3a to tip downward; but it passes without moving the shaft 4 or the switch contacts 8 and 9, and the counter weights return the arm 3a to normal position when released by the pin 2 moving downward. Figure 4 shows only one of several types of automatic re-opening switches that may be used in the alarm circuit at 13, Figure 1.

The line terminal contacts 25 on the transmitter 22 are low voltage contacts energized at all times during which the transmitter is connected to the power supply through contacts 23 and wall plug 30 or through a battery connection if the transmitter is battery operated. These contacts 25 provide the electric current which energizes the alarm switches 3, 13, 33, the alarm relay coils 12, 101, the electric motor 42 and the filament of tube 29.

The temperature controlled fire alarm switches 33 shown in Figure 1 are similar in operation to the burglar alarm switches 13. It will be noted that the use of automatic re-opening switches 13 and 33 and the use of automatic re-closing switches, such as those described (130, 130a) cooperating with contacts 49 and 49a (Figure 1) make this alarm system entirely automatic in operation. After each operation, the alarm system is again ready to send another alarm as the alarm circuit is again open. For instance, if a burglar attempts to enter the premises an alarm is given even if the attempt is unsuccessful. If a second attempt is made after some time, the alarm is repeated. It should be noted here that the switches 13, and 33 are to be considered as an example of one type that might be used. Their construction and arrangement does not form part of this invention.

The operation of the arrangement is as follows:

Assuming that the relay circuit 16 belongs to the burglary alarm circuit, while the circuit 100 belongs to the fire alarm circuit; then it will be clear that if one of the switches 13 is closed by an unauthorized person entering the premises, while the key-operated switch 32 has been closed or when one of the switches 3 is closed momentarily by the owner of the property being protected, the circuit of relay 12 will be closed run-

ning from the negative terminal of contacts 25 over leads 70, relay coil 12, switch 13 which has been closed by the intrusion, switch 32, lead 72, relay arm 14, leads 15 and 82a to positive terminal of contacts 25. Relay 12 is energized and operates the relay arms 14, 16, 17, 18 and 19. Arm 16 closes a holding circuit from source 25, over 82a, over contact 20 through lead 79, switch arm 130, contact 49 and conductor 79a which holding circuit is parallel to the lead 72 and to the switches 3, 13. A re-opening of the switch 13 or 3 which has been closed or even destruction of the same, therefore, does not affect the operation of the alarm system. Operation of the arm 14 opens the circuit of the switches 3, 13 and causes the control of the relay holding circuit to be left with switch contact arm 130 and contact 49 operated by the worm gear arrangement 47. Arm 17 operates a switch which is part of the transmitter and which closes the circuits of the filaments of the electronic tubes in the transmitter. These circuits are connected with contacts 24 of the transmitter 22 over leads 73 and 74 and are normally open until closed by relay arm 17.

The relay arm 18 controls the circuit supplying current to the filament of the electronic tube 29 and also the circuit to the motor 42. The circuit to motor 42 runs from the negative terminal at 25 on the transmitter through lead 70, through relay arm 18, through lead 82 to motor 42 and back through lead 81, through relay contacts 31 to positive terminal at 25.

The purpose of the electronic tube 29 and the relay 28 is to delay the operation of the motor 42 until the electronic tubes in the transmitter 22 have warmed up sufficiently and the transmitter is actually broadcasting on its carrier frequency.

When the relay arm 18 closes it energizes the filament of tube 29. When the tube 29 has become heated a plate current will begin to flow and close the relay contacts 31 by energizing the relay closing coil 28. The tube 29 is of the same general type to which the transmitter tubes belong and it is so selected that its warming up time will be either the same or slightly longer than that of the transmitter tubes. The relay 28 is therefore operated when the transmitted tubes are ready for operation. It completes the circuit to the motor 42 and the motor now starts to run drawing along the pulleys 45 with the magnetized wires by means of the gear wheels 44 and the pulley 43. The magnetized wires when passing the magnetic heads with the coils 50 and 51 are engendering the talking currents; only the circuit of coil 50 is closed by the armature 19, as this armature connects contacts 26 of transmitter 22 leading to the modulating arrangement of the transmitter with the coil 50 by means of leads 83, 83a, 84 and 85.

The transmitter is modulated by the talking currents generated in coil 50 which produce the required signal calling the police station and stating that a burglary signal has been operated and further stating the exact location of the premises.

The call is repeated several times. The length of the period during which the call is issued is selected appropriately. When the motor 42 starts to operate it turns not only the pulley 43 but also worm gear 46 and the worm wheel 47 on which a cam surface or pin 48 is mounted. When the wheel 47 has been turned around for one revolution, the cam or pin 48 pushes the switch operating lever 124 to the side against the action of spring 125. Further rotation of the wheel

47 causes the pin 48 to press against the switch actuating lever 124 and to move it outwardly away from rest 126 until it has reached the end of the lever. When further advanced the switch actuating lever snaps back and strikes against the push rod 127 which is connected with the two contact levers 130, 130a cooperating with the contacts 49, 49a. These levers under the impact of the lever 124 striking against the push rod 127 are pushed away from lever 124 against the action of their spring 128 associated with them and they will be separated from contacts 49 and 49a for a short while. The lever 124 comes to a rest against stop 126 and the two levers 130, 130a return under the influence of their spring 128 and come into contact with the contacts 49, 49a.

The opening of the holding circuits at contacts 49 and 49a causes deenergization of the relay 12. The said relay, when deenergized falls back and the circuits controlled by the relay arms 16, 17, 18, 19 are again opened while relay arm 14 simultaneously closes its contact connected with line 15.

It will be noted that the worm gear arrangement is so adjusted that the gear wheel 47 will complete one revolution by the time the recorded message on one of the endless wires 41, 41a has been broadcast the desired number of times. The disconnection and return of the apparatus therefore occurs when a complete cycle of operations has been performed. Since the switch arm 130 is again in contact with contact 49 and the relay arm 14 is closed, completing circuits to the alarm switches 3 and 13, the entire alarm system is now again ready for another operation.

The push-button switches 3 are provided so that the tenant of the property can operate the alarm system in case of a robbery attempt while the tenant is on the premises.

The alarm apparatus, is usually combined with some local apparatus (not shown) giving a local alarm at the place itself or at a suitable place in the vicinity, and it is returned to its normal condition when the local alarm is stopped or the necessary counter-measures have been taken.

In the event of a fire the heat causes one of the switches 33 to close (momentarily). This closes the circuit 100 of relay 101 through the relay contact arm 114 and switch 33.

The operation is similar to that which has already been described. The relay 101 is energized and operates all the circuits which have been described in connection with relay 12 with the exception that contact arm 119 now closes the circuit of coil 51 and connects it with contacts 27 of the transmitter 22 which also leads to the modulating arrangement over leads 91 and 92. The wire 41a now furnishes the talking currents calling the fire department and stating the location of the premises where the fire has broken out. The relay arm 116 closes the circuit to the switch contact 49a which contact is opened (momentarily) when the gear wheel 47 completes one revolution and pushes contact arm 130a away from it. This action stops the operation of the entire alarm system apparatus in the same way in which the opening of the contact 49 stops the operation of the system.

The modification shown is designed for conditions in which alarm has to be given to one agency, say the police station only, which will notify other agencies such as the fire department, if necessary. If independent agencies are to be notified the relays have to operate two transmitters or a plurality of transmitters, practically

all arranged together and forming a single transmitter with a plurality of frequencies. The operation of a transmitter with a plurality of frequencies may be controlled by providing as many contacts 24 as there are frequencies and by operating them separately by the contact arms 16, 116 in the same way in which the coils 50, 51 are operated separately.

Other modifications and changes will be obvious to persons skilled in the art.

I claim:

1. An alarm system for unguarded premises having an alarm circuit with temporarily closing alarm contacts, a self-holding alarm relay provided with relay arms and contacts, and operated by said contacts, and a holding circuit for the said relay, and further provided with a broadcast transmitter having electronic tubes and an energizing circuit, closed and held closed by the arms and contacts of the alarm relay, when operated, and further including a source of currents, means for producing radio frequency oscillations and means for modulating the said oscillations by recorded speech currents, the latter means including an endless record carrier, means for advancing the same, and electric driving means for said advancing means, said alarm system comprising an energizing circuit for the record carrier driving means, controlled by the relay contacts of the alarm relay, simultaneously with the control of the energizing circuit of the broadcast transmitter, an electronic tube connected with said transmitter provided with a cathode and a plate, supplied with heating and plate current upon energization of the transmitter, and thus becoming operative simultaneously with the electronic transmitter tubes, a plate circuit for said tube, a control relay in said plate circuit, operated upon operation of the tube, said control relay including a relay contact controlling the energizing circuit of the electric driving means for the record advancing means, means for limiting the advance of the endless record carrier, including a pair of normally closed contacts, one of said contacts being displaceable, means for displacing said displaceable contact operated by said driving means of the endless record carrier after a predetermined advance of the said endless record carrier, said contact pair controlling the holding circuit of the alarm relay and thereby controlling the circuit of the electric driving means for the endless record carrier and the energizing circuit of the transmitter, the advance of the endless record carrier and the operation of the broadcast radio transmitter being thus synchronized in order to obtain a predetermined number of messages during a minimum of broadcasting time.
2. An alarm system for unguarded premises having an alarm circuit with temporarily closing alarm contacts, a self-holding alarm relay, provided with relay arms and relay contacts and operated by said alarm contacts, and a holding circuit for the said relay, and further provided with a broadcast transmitter having electronic tubes, an energizing circuit, closed and held closed by the arms and contacts of said alarm relay, when operated, and including a source of currents, means for producing radio frequency oscillations, and means for modulating the same by recorded speech currents, the latter means including an endless record carrier, rotating means for advancing the same, and electric driving means for said endless record carrier, driving said rotating advancing means, said alarm system com-

prising an energizing circuit for the record carrier driving means, controlled by the relay contacts of the alarm relay, simultaneously with the controlling of the energizing circuit of the broadcast transmitter, an electronic tube connected with said transmitter, provided with a cathode and a plate and supplied with heating and plate current upon energization of said transmitter, thus becoming operative simultaneously with the electronic tubes of the transmitter, a plate circuit for said tube, a control relay in said plate circuit operated upon operation of the tube, said control relay including control relay contacts controlling the energizing circuit for the electric driving means for the endless record carrier, a heating circuit for the cathode of the aforesaid electronic tube arranged in parallel to the control relay contacts in the energizing circuit of the electric driving means for the endless record carrier, rotating pulleys driven by said driving means and advancing said endless record carrier, and a revolution counter, including a pair of normally closed contacts separated after a predetermined rotary movement of the said pulleys, said contacts controlling the holding circuit of the alarm relay and thereby the energizing circuits for the

electric driving means of the endless record carrier and the energizing circuit of the transmitter, and de-energizing said circuits upon operation after a predetermined number of revolutions of the pulleys.
